UNITED STATES PATENT OFFICE.

SYLVESTER H. ROPER, OF BOSTON, MASSACHUSETTS.

FIRE-ESCAPE.

SPECIFICATION forming part of Letters Patent No. 516,116, dated March 6, 1894.

Application filed May 19, 1893. Serial No. 474,762. (No model.)

To all whom it may concern:

Be it known that I, SYLVESTER H. ROPER, of Boston, in the county of Suffolk and State of Massachusetts, have invented certain new 5 and useful Improvements in Fire-Escapes, of which the following is a specification.

This invention relates to that class of fire-escapes in which an object or person is lowered by means of a line which unwinds from 10 a reel or drum.

An apparatus embodying these features is shown in my former patent, No. 439,191, granted October 28, 1890, and means are there illustrated whereby a suitable fluid may be 15 employed as a retarding agent to prevent too rapid rotation of the reel or drum in unwinding.

The object of the present invention is to provide improved means for securing this retarding effect through the agency of a fluid. 20

To this end, the invention may be said to consist in combining with the reel or drum a cylinder arranged to rotate therewith and adapted to contain the fluid, a piston in said 25 cylinder, means whereby the rotary motion of the cylinder is converted into reciprocating motion of the piston endwise of the cylinder, and a restricted passage affording communication from one side of the piston to the 30 other.

The invention also consists in certain novel features of construction and combinations of parts hereinafter described and claimed.

The accompanying drawings illustrate a 35 construction by which the invention may be carried out.

Figure 1 shows a side elevation of the complete apparatus, the suspending chain being broken, and the inner and outer convolutions 40 of the line or tape being indicated in broken lines. Fig. 2 shows a section on line 2—2 of Fig. 1. Fig. 3 shows a section on line 3—3 of Fig. 2. Fig. 4 shows a detail perspective view of a portion of the cylinder represented 45 as broken away. Fig. 5 shows a detail of the piston.

The same letters of reference indicate the same parts in all the figures.

In the drawings: The letter *a* designates a 50 casing, which is adapted to be suspended from a suitable fixed support, as a sill, by means of a chain *a'* attached to it and having

a hook *a*² at its free end. Thus the said casing will be held practically stationary. A spindle *b* extends through the said casing, and 55 a drum or reel *b'* is mounted on said spindle. A line, preferably a steel tape *c*, is attached to the drum, and winds on the same within the casing, the latter having an opening in one side through which the tape issues from 60 the case. An extension *b*² of the spindle *b* projects from one side of the casing, and a cylinder or chamber *b*³ surrounds said extension and is fast with the drum *b'*, being preferably formed integral therewith. A shoulder 65 *b*⁴ is formed between the drum and cylinder, and a plate *a*³ fits around the drum and against the shoulder and forms one side of the casing, said plate being preferably fast with the drum, so that it turns therewith. A 70 shoulder *b*⁵ is preferably formed between the spindle and the extension thereof, and fits against the inner end of the cylinder *b*³. The outer end of the cylinder is closed by a head *b*⁶, which is fastened on by screws *b*⁷, and bears 75 against the outer end of the spindle extension *b*². The spindle extension and the cylinder are concentric, and a piston *d* is fitted on said extension and is adapted to reciprocate in the cylinder. Reciprocations of the piston are 80 brought about through the rotation of the cylinder, and the means here shown for effecting this conversion of motion consist in a cam-groove *e* encircling the piston, and a pin *e'* set in the cylinder and engaging said groove. 85 The piston is splined to the spindle-extension by means of a feather *e*², so that rotation of these parts independent of each other is prevented, and the piston is properly guided. A restricted passage affords communication 90 from one side of the piston to the other, and in the present instance this passage, which is designated *f*, extends through the spindle-extension *b*², entering one side of the same at the inner end of the cylinder, and thence extending longitudinally of said spindle-extension 95 to the outer end thereof, the restriction being effected by means of small grooves *f*² in the end face of the spindle-extension and radiating from the passage *f*. A set-screw *g*, 100 inserted in the cylinder-head *b*⁶, has its end in the passage *f*, and affords means for regulating the amount of restriction.

The cylinder *b*³ is filled with fluid, prefer-

ably glycerine on account of its density, and the operation is as follows: The apparatus being suspended from a rigid support, the object or person to be lowered is attached to the tape *c*, the latter being provided at its end with suitable means such as a band *c'*, to facilitate the attachment, and the weight of such object or person unwinds the tape from the drum which revolves on the spindle *b'*. The cylinder *b*³ being fast with the drum, it is likewise revolved, and its revolution causes the piston *d* to be reciprocated through the means described. In the reciprocations of the piston, its end-faces constitute walls, which advance upon the inclosed fluid, and drive it from one end of the cylinder to the other through the restricted passage *f*, and the restriction of said passage produces a resistance to the piston and consequently to the rotation of the cylinder and drum. It is evident the tape can unwind only in a limited degree of speed, and hence an object or person may be lowered with perfect safety. Provision is made for re-winding the tape while the resistance is dormant, as follows: The spindle projects from the case *a*, as at *a'*, and a ratchet *h* is affixed to it, in the present instance by flattening two sides of the spindle and correspondingly shaping the opening in the ratchet which receives the spindle, and by screwing a nut *h'* on the end of the spindle, which is threaded for the purpose, and clamping the ratchet between it and a shoulder *h''* of the spindle. The ratchet works close to the case, and a pawl *h*³ is pivoted to the latter and pressed into engagement with the ratchet by a spring *h*⁴. The direction of rotation of the drum during the unwinding of the tape is such that the pawl *h*³ forms a stop, which prevents rotation of the ratchet and consequently of the spindle, and hence the drum turns on the spindle and reciprocating motion is imparted to the piston, as before described. When the drum is rotated in the reverse direction, however, the pawl no longer acts as a stop, and the ratchet may freely pass it. Hence the drum and spindle move together during rotation in this latter direction, and the cylinder and spindle-extension being fast with the drum and spindle respectively, they also move together and carry the piston with them, so that no reciprocation of the latter takes place, and hence the resistance is absent. The tape may be rewound by means of a crank *i*, adapted to be screwed into a threaded hole *i'* in the edge of the cylinder-head *b*⁶. When not in use, this crank may be conveniently carried in a holder *j* fastened to the case *a*.

It is evident that numerous changes might be made in the construction here shown, without departing from the spirit of the invention. The restricted passage by which

communication is afforded from one side of the piston to the other might be by other channels than those here illustrated. For example, the piston could have a loose fit, which would permit passage of the fluid. The structure is susceptible of many variations, and hence the invention is not limited to the specific means by which I have here chosen to illustrate it.

Having thus described my invention, what I claim as new, and desire to secure by Letters Patent, is—

1. A fire-escape, comprising in its construction a rotatable drum suitably supported, a line attached to said drum, a cylinder arranged to rotate with the drum, a piston in the cylinder, means for converting rotary motion of the cylinder into reciprocal motion of the piston endwise of the cylinder, and a restricted passage affording communication from one side of the piston to the other. 75

2. A fire-escape, comprising in its construction a rotatable drum suitably supported, a line attached to said drum, a cylinder arranged to rotate with the drum, a piston in the cylinder, means for converting rotary motion of the cylinder into reciprocal motion 80 of piston endwise of the cylinder, such means consisting of a cam-groove in one part and a projection on the other part engaging said groove, and a restricted passage affording communication from one side of the piston 90 to the other. 95

3. A fire-escape, comprising in its construction a spindle and support therefor, a drum on said spindle, a line attached to said drum, a cylinder arranged to rotate with the drum 100 and surrounding an extension of the spindle, a piston in the cylinder and around the spindle, a restricted passage extending through the spindle and affording communication 105 from one side of the piston to the other, and means for converting rotary motion of the cylinder into reciprocating motion of the piston.

4. A fire-escape, comprising in its construction a spindle and support therefor, a drum 110 on said spindle, a line attached to said drum, a cylinder arranged to rotate with said drum, a piston in said cylinder, a restricted passage 115 affording communication from one side of the piston to the other, means for converting rotary motion of the cylinder into reciprocal motion of the piston, a ratchet on the spindle, and a pawl on the spindle-support and engaging said ratchet.

In testimony whereof I have signed my 120 name to this specification in the presence of two subscribing witnesses.

SYLVESTER H. ROPER.
